ERNST KESSLER, OF STUTTGART, GERMANY.

MACHINE FOR MARKING WEBS OF FABRIC, PAPER, AND THE LIKE.

1,169,495.

Specification of Letters Patent. Patented Jan. 25, 1916.

Application filed December 30, 1914. Serial No. 879,725.

To all whom it may concern:

Be it known that I, ERNST KESSLER, a citizen of the German Empire, residing at Stuttgart, in the Kingdom of Wurttemberg, 5 Germany, have invented new and useful Improvements in Machines for Marking Webs of Fabric, Paper, and the like; and I do hereby declare the following to be a full, clear, and exact description of the invention, such as will enable others skilled in the art to which it appertains to make and use the same.

My invention relates to improvements in machines for marking webs of fabric, paper, 15 and the like, and the object of the improvements is to provide a machine of this class in which the web is fed by means of two pairs of clamping bars which are reciprocated in line with each other and in opposite 20 directions toward and away from each other, and which are alternately thrown into clamping engagement with the web, and which are provided with the means for applying the mark to the web, said clamping 25 bars coöperating with a web carrier in the form of a band which supports the web substantially over the whole surface thereof which is being engaged by the clamping members, so that no strain is exerted on the 30 web by gravity. Thereby I am enabled to feed webs of different thickness or elasticity in a uniform way, so that the marks are applied at exactly predetermined distances away from one another.

By means of my improved machine I am 35 enabled to apply to the web marks of any kind, such for example as marks for indicating the length of the sections of the web, business marks, advertising marks, and the like, and the marks can be applied to the web at any desired distance.

In the preferred form of the machine I prefer to connect the clamping means with the means for supporting the web in such 45 a way, that the feeding of the carrier is effected independently of the carrier itself and in such a way that no strain is exerted on the carrier.

For the purpose of explaining the invention an example embodying the same has 50 been shown in the accompanying drawings,

in which the same characters of reference have been used in all the views to indicate corresponding parts.

In said drawings—Figures 1 and 2, are 55 diagrams illustrating the operation of the clamping bars, Figs. 3 and 4, are side views showing respectively the right and left hand parts of the machine, Figs. 5 and 6 are plan views of the parts of the machine shown in 60 Figs. 3 and 4, Fig. 7, is an enlarged detail view partly in section showing parts of one pair of the clamping bars and the telescoping driving means connected to one of the 65 clamping bars, Fig. 8, is an enlarged detail view partly in section and showing the other pair of clamping bars and the locking mechanism therefor, Figs. 9 and 10, are detail views showing a part of the clamping 70 bars shown in Fig. 7 and the driving mechanism for the marking apparatus, Figs. 75 11 to 13, are views showing the marking apparatus, Fig. 14, is an enlarged detail view showing a part of the mechanism illustrated in Fig. 12, and Figs. 15 to 19 are views of the moistening apparatus.

Referring to the example illustrated in the drawings, my improved machine consists of a pair of lateral frame members 29, 29 which are formed at their upper ends 80 with lateral arms 29^a, 29^a, and which are suitably braced apart by transverse rods 29^b. On the tops of the lateral arms brackets 25, 25 are secured which provide supports for longitudinal guide rods 13, 13 located one at each side of the machine. On the said guide rods a pair of lower clamping bars 1, 3 are mounted for reciprocation which coöperate each with an upper clamping bar 2 and 4 respectively for feeding the 90 web of fabric or the like. The clamping bars 1, 2 and 3, 4 are adapted to be reciprocated on the guide rods 13 in opposite directions and from opposite ends to the middle thereof and back again, and such reciprocating 95 movements are imparted to the clamping bars by means of endless chains 9, 10, 11, 12 which are trained on sprocket wheels 5, 6, 7, 8 which are mounted for rotation on vertical shafts 9^a, 12^a secured to inner lugs 100 9^b, 12^b of the side frames 29. As appears more particularly from Fig. 7 the clamping

bar 1 is formed at its ends with vertical guide ways 1^a on which slides 23, 24 are vertically movable. To the said slides shafts or trunnions 21, 22 are secured which carry 5 at their inner ends rollers 31 and 32 respectively which engage longitudinal guide grooves 13^a and 14^a of the guide rods 13 and 14. Furthermore beveled gear wheels 19, 20 are mounted on the shafts 21, 22 by 10 means of which rotary movement is imparted to gear wheels 17 and 18 by mechanism to be described hereafter. The gear wheels 17 and 18 are secured to or made integral with the beveled gear wheels, and 15 they are adapted to roll on racks so that their rotary movement is transformed into rectilinear movement of the slides 23 and 24 and the clamping bar 1. This rectilinear movement is transmitted to the clamping 20 bar 3 through the chains 9, 10, 11, 12.

The construction of the said racks will be best understood from an inspection of Fig. 3. As shown plates 15 and 16 are secured one to each side of the frame members 29, and the 25 said plates are provided with elongated openings formed at their side walls with internal rack teeth, the plate 15 being provided with upper rack teeth 15^a, lower rack teeth 15^b, and lateral rack teeth 15^c, so that an end- 30 less rack is formed which is engaged by the pinion 17. The elongated opening of the plate 16 is formed at its walls with similar internal rack teeth which are not shown in the drawings, the rack teeth of the plate 16 35 being engaged by the pinion 18. When the bevel gear wheels 19 and 20 are being rotated the gear wheels 17 and 18 roll on the lower lateral and upper parts of the racks, and in order that the rolling movement be free of 40 shocks which might be caused when the gear wheels 17 and 18 pass from the lower parts to the lateral ones, or from the lateral parts to the upper ones, the lateral and upper and lower parts merge into each other through 45 circular portions as will readily be understood from an inspection of Fig. 3. When the gear wheels 17 and 18 pass from the lower parts of the racks through the lateral parts and to the upper ones, the direction of 50 the travel of the clamping bars 1 and 3 is reversed. The lateral portions of the racks are provided in order to make sure that the movement be reversed exactly at the end of the upper and lower parts of the racks. 55 Preferably the lateral rectilinear portions are made as short as possible, in order that the gear wheels 17 and 18 pass through the same within a moment, and the movement of the clamping bars and the web of fabric fed 60 thereby is interrupted during as short a period as possible.

In order that the gear wheels 17 and 18 follow their paths along the racks, they are guided by means of the rollers 31 and 32 65 rolling on the longitudinal grooves of the

rails 13 and 14. While the gear wheels 17 and 18 roll on the racks the rollers 31 and 32 rolling on the grooves of the rails 13 and 14 prevent the same from getting out of engagement with the racks. At the ends of 70 the grooves 13^a and 14^a of the rails 13 and 14 pins 33, 34, 35, and 36 are secured to the latter, and the upper and lower grooves 13^a and 14^a are connected at their ends by transverse grooves 63, 64, 65, 66. 75

The clamping bars 1 and 3 are so connected with each other through the chains 9, 10, 11, 12, that the bar 1 reciprocates on the left hand portion of the rails 13, 14 and the bar 3 on the right hand portion thereof, 80 and that both bars meet at the middle of the said rails.

The upper clamping bars 2 and 4 which coöperate with the bars 1 and 3 for clamping and feeding the web of fabric or the like 85 are yieldingly connected with the lower bars 1 and 2. As appears more particularly from Figs. 3, 5 and 7, bolts 37 and 38 are secured to the lower clamping bar 1 and pass through bores made in the upper clamping bar 2. 90 Between the heads of the said bolts and the top of the clamping bar 2 springs 37^a and 38^a are coiled around the bolts which exert clamping pressure on the bar 2 and force the same in yielding contact with the clamping bar 1. In a similar way spring actuated bolts 39 and 40 are secured to the upper clamping bar 4 and pass through bores made in the bar 3, so that the said clamping bars are yieldingly forced in clamping engagement 95 with each other, as is shown in Figs. 4, 5, 6, and 8. The lower surfaces of the bars 2 and 4 are provided with linings 41 and 42 which deaden the shock when moving the bars 1, 2, and 3, 4 in clamping engagement and release an excessive pressure which would otherwise be exerted by the clamping bars on the web interposed between the same. 100

Between the clamping bars 1, 2, 3, 4 an endless supporting band 44 is interposed 110 which is trained on rolls 45, 46, 47, and 48 and extends over the whole breadth of the operative part of the machine. To prevent the band from being shifted laterally longitudinal belts 44^a of leather or rubber are 115 secured to the inner surface thereof by gluing, sewing, or the like, and the said belts engage in annular grooves of the rolls 45, 46, 47 and 48 and the rails 1, 3. 120

To release the clamping bars 1, 2 and 3, 4 from the tension which is necessary for carrying the band 44 along, the band guiding roll 46 is provided with driving means of its own. As shown, on trunnions 46^b of the said roll sprocket wheels 49 and 50 are 125 loosely mounted which are adapted to be coupled to the roll by means of spring actuated clutch members 57 and 58, the clutch jaws of the parts 49, 57 and 50, 58 being oppositely directed, so that one of the 130

clutches is operative for rotation of the roll in one direction and the other one for rotation in the opposite direction. On trunnions 55 and 56 secured to the plates 15 and 16 sprocket wheels 53 and 54 are loosely mounted, and on the sprocket wheels 49, 53 and 50, 54 chains 51 and 52 respectively are trained. The upper stretch of the chain 52 is secured to the rear end of the clamping bar 3, and the lower stretch of the chain 51 is secured to the front end of the clamping bar 3, so that the sprocket wheels 49 and 50 are rotated in opposite directions.

In the positions of the parts shown in the drawings the gear wheels 17 and 18 move from the left to the right, so that the pairs of clamping bars 1, 2 and 3, 4 move in opposition to each other, as has been indicated in Fig. 1 by the arrows. The pair of clamping bars 1, 2 are in clamping engagement with the supporting band 44 and the web of fabric 43 placed thereon, while the clamping bars 3, 4 are out of clamping engagement. As the gear wheels 17 and 18 roll on the racks 15, 16 the pairs of clamping bars are approached toward each other by means of the chains 9, 10, 11, 12, so that the web of fabric clamped between the bars 1 and 2 and supported on the band 44 is carried along in the direction of the arrows. In this case the supporting band 44 is rolled off by the tension of the chain 51 acting on the guide roller 46, the sprocket wheel 49 being in engagement with the clutch member 57, so that it is rotated in the direction for unwinding the supporting band. In the meantime the sprocket wheel 50 is rotated in the opposite direction, because the upper stretch of the chain 52 is attached to the bar 3, and the clutch jaws of the sprocket wheel 50 ride on the jaws of the clutch member 58.

When the gear wheels 17 and 18 moving from the left to the right engage in the vertical or lateral portions of the racks 15 and 16, the part of the movement of the clamping bars indicated in Fig. 1 by the arrows is finished. Now the direction of the movement is reversed, and simultaneously the pair of clamping bars 1, 2 which before was in clamping position is thrown in non-clamping position, and the pair 3, 4 which was in non-clamping position is thrown in clamping position. This change in the operation of the parts is performed while the gear wheels 17 and 18 move along the vertical portion 15^c of the rack, and the slides 23 and 24 moving upward within the guide ways 1^a formed in the clamping bar 1 separate the bar 2 from the bar 1 and hold the same in the position shown in Fig. 2 by engaging with their top faces below the ends of the said bars. Simultaneously spring actuated locking bolts 59 and 60 provided in the clamping bar 3 in position for locking

engagement with the bolts 39 and 40 get in contact with stop lugs 61 and 62 provided on the machine frame so as to be thrown out of locking engagement with the spring actuated bolts 39 and 40, so that the latter throw the clamping bars 3 and 4 into clamping engagement. While the positions of the clamping bars are being changed the rollers 31 and 32 pass through the transverse grooves 63 and 64 of the guide rails 13 and 14.

After the clamping and releasing operations have thus been reversed, the clamping bars start their movement in the reverse direction, as has been indicated in Fig. 2 by the arrows, the gear wheels 17 and 18 which are being rotated in the same direction as before engaging in the upper sections 15^a of the racks, so that the pair of bars 1, 2 is moved from the right to the left and, through the chains 9, 10, 11, 12 the pair of clamping bars 3, 4 from the left to the right. Now the pair of clamping bars 3, 4 has the function to advance the web of fabric in the direction of the arrows shown in Figs. 1 and 2. The supporting band 44 is unrolled from the roll 46 by means of the chain 52, the sprocket wheel 50, and the clutch 58.

The movement of the clamping bars away from each other is finished, when the gear wheels 17 and 18 arrive in the opposite vertical parts 15^c of the rack, whereupon the rollers 31 and 32 pass through the transverse grooves 65 and 66. Thereby the slides 23 and 24 of the clamping bar 1 are pulled downward so as to release the upper clamping bar 2 and permit the same to be forced downward by the springs coiled around the bolts 37 and 38, so that the pair of clamping bars 1 and 2 gets in clamping engagement. Now rollers 67 provided on the slides 23, 24 engage on the top faces of shoes 68 provided on rocking levers 69 located one on each side of the machine frame, as is shown in Figs. 3 and 4. Thereby the rocking levers 69 are rocked with their opposite ends upward, so that shoes 70 provided at the opposite ends shift the bolts 39 and 40 upward, which at this moment are in positions for engagement by the shoes. Thereby the bar 4 is lifted from the bar 3. In the uppermost position of the bar 4 the spring bolts 59, 60 get into locking engagement with the spring bolts 39 and 40 and hold the upper bar 4 in position, until the locking bolts are again thrown out of locking position by the stop members 61 and 62, as has been described above.

The driving mechanism for the gear wheels 17 and 18 is constructed in the following way: Referring to Figs. 3, 5 and 7, the bevel gear wheels 19 and 20 are connected with the wheels 17 and 18 and are mounted therewith on the shafts 21 and 22 respectively secured to the slides 23 and 24.

The bevel gears are in mesh with bevel gear wheels 72 and 73 the hubs of which are secured to sleeves 74. Through cylindrical bores of the hubs of the bevel gears 72 and 5 73 stub shafts 75 and 76 are passed which are formed at their upper ends with transverse eyes 75^a and 76^a by means of which they are suspended from the shafts 21 and 22. At their lower ends the said stub shafts 10 are screw-threaded and on the said screw-threads nuts 75^b are screwed which engage below the hubs of the gear wheels and force the same in contact with shoulders 75^c formed on the shafts 75. Thereby the bevel 15 gears are held in their proper positions relatively to the shafts 21 and 22. To the outer ends of the shafts 21 and 22 sleeves 77 and 78 are secured which hold the eyes 75^a and 76^a in their positions on the shafts 21 and 22. 20 At their lower ends the sleeves 74 are engaged by shafts 81 which are connected therewith by feathers 80 and slits 79, so that the parts are slideable relatively to each other, while rotation is transmitted from the 25 shafts 81 to the sleeves 74. To the lower ends of the shafts 81 bevel gears 82 and 83 are screwed the hubs of which are embraced by bearing plates 84, 85 (Fig. 3) which hold the said hubs and bevel gears in the proper 30 position relatively to bevel gears 86 keyed to a main driving shaft 87. The bevel gears are held in position on the shafts 81 by nuts 88 and 89 screwed to the shafts 81. The bearing plates 84 and 85 are rigidly secured 35 by screw bolts and nuts 84^a and 84^b to bearing plates 90 mounted on the shaft 87. The bearing plates 90 are held in position on the shafts 87 by sleeves 91. Power is supplied to the shaft 87 from an electromotor E 40 through gear wheels 92, 93.

While in the foregoing I have described the mechanism for feeding the web of fabric along a plane, I shall now describe the mechanism for applying marks to the fabric. 45 In the example shown in the figures the pair of clamping bars 1 and 2 carries the mechanism for applying the marks. As appears more particularly from Fig. 9 a rod is slidably mounted on the bar 2 which consists of a cylindrical part 94 and a flat part 94^b. The cylindrical part is guided in a bracket 94^c provided on the top of the bar 2, and the flat part 94^b is guided between a pair of lugs 97 and 98 provided on the bar 2 and 50 preventing rotation of the rod 94. The rod 94 is adapted to be shifted in longitudinal direction by means to be described hereafter, and when shifted in forward direction and into the position shown in Fig. 9 in dotted lines, a nose 100 formed at its end is engaged by a spring actuated pawl 101 which is pivotally mounted on the top side of the bar 2. To the cylindrical part of the rod 94 55 two nuts 95 and 96 are secured, and between the nut 95 and the noses 97 and 98 a spring 60

99 is coiled around the rod which tends to shift the same rearward in Fig. 2 and into the position shown in full lines. The nuts 95 and 96 are located on opposite sides of an arm 102^a of a slide rod 102 which takes 70 part in the movements of the rod 94 and is slidably mounted on a plate 103 secured to the bar 2 by screws 104, 105.

For imparting longitudinal movement to the rod 94 the following mechanism is provided: The rod 94 is formed with rack teeth 94^a which are in mesh with the teeth of a pinion 106 mounted on a stub shaft 108 and rigidly connected with a gear wheel 107 secured to the bar 2. The pinion 106 is 80 rigidly connected with a gear wheel 107 the teeth of which are in mesh with a pinion 109 the hub of which is mounted in a corresponding bore of the bar 2 and held therein by a ring 112 secured to the said hub and 85 engaging at the rear of an annular shoulder 112^a. The pinion 109 is rigidly connected with a crank arm 110 having a crank pin 111. Through a bore of the hub of the pinion 109 and the crank 110 a stationary stub 90 shaft 113 is passed which is screwed into the bar 1. On the stub shaft 113 a gear wheel 114 is mounted for rotation which is formed with an arc shaped slit 115 which is adapted to be engaged by the crank pin 95 111 when the bar 2 has been lifted from the bar 1. The stub shaft 113 is provided with two collars 116 and 117 which are adapted to be engaged by the cylindrical end of a screw 118 screwed into the hub of 100 the gear wheel 114 and are adapted to lock the gear wheel 114 as against displacement axially of the stub shaft 113. The gear wheel 114 is in engagement with a pinion 119 which is rigidly connected with a gear 105 wheel 120. The pinion 119 and the gear wheel 120 are mounted for rotation on a shaft 121 which is screwed into the bar 1, and they are locked as against longitudinal 110 displacement away from the bar 1 by a nut 122. The gear wheel 120 is in engagement 115 with a rack 123 which is secured to the plate 15. Therefore, when moving the pair of clamping arms 1, 2 in the manner described above the gear wheel 120 rolls on the rack 123, the direction of the rotation of the gear wheel depending on the direction of the travel of the clamping bars. When the latter are moving in the direction toward the clamping bars 3, 4, as has been indicated 120 in Fig. 1, the gear wheel 120 when seen from above in Fig. 9 rotates in the direction of the hands of a clock, and when the pairs of clamping bars move in the direction away 125 from each other, as is indicated in Fig. 2, the gear wheel 120 rotates in the opposite direction. As the gear wheels 114 and 119 take always part in the movement of the clamping bars and the rotation of the gear wheel 120, while the rod 94 must be at rest 130

when applying the marks to the fabric, the gear wheels 109 and 114 must be temporarily disconnected. This is done by means of the crank 110 and its pin 111 which are adapted to be shifted axially of the gear wheel 114 together with the clamping bar 2.

While the clamping bars 1 and 2 are in clamping position, as has been shown in Fig. 10, the gear wheels 109 and 114 are disconnected and the rod 94 is free to be moved by the spring 99 in the direction of the arrow, as soon as the locking pawl 101 is retracted from the nose 100. This is done when the pawl is engaged by a pin 124 secured to the plate 15. When the rod 94 is being shifted into the position shown in Fig. 9 in dotted lines, also the bar 102 is shifted from the position shown in dotted lines in Fig. 11 and into the position shown in the said figure in full lines. In order that racks 102^b and 102 formed on the rod 102 remain in engagement with gear wheels 125 and 126, the rod 102 is guided on feathers 127 and 128 secured to the plate 103.

In Figs. 11, 12 and 13 I have shown further parts of the marking mechanism which are mounted on the plate 103, the object of the said parts being to effect the marking together with the bar 2, the rod 94, and the slide bar 102. As shown a roll 130 is loosely mounted on a stub bolt 129 secured to the plate 103, which roll is adapted to receive a perforated marking web 132 rolled on a sleeve 131. To prevent the sleeve 131 from falling off the bolt 129 a screw 133 is fitted therein which engages with its cylindrical end in an annular groove 134 of the bolt 129. As is shown in Fig. 14, the head of the screw 133 and also that of a screw 188, engages in a slot of the sleeve 131 and locks the sleeve 131 as against displacement relatively to the roll 130. The marking web 132 is passed over pins 135, 136, 137, and 138 and to a drum 139 provided with conical pins 140 which engage in holes made in the web of marking paper and at one side thereof, whereby the marking web is positively driven from the drum. The drum is loosely mounted on a bolt 141 which is secured into the plate 103. To the hub of the drum 139 a ratchet wheel 142 is rigidly secured, and at the rear of the said ratchet wheel a dish shaped disk 143 is loosely mounted on the bolt 141 which is formed at its center with an opening and which has a spring 144 wound about its circumference. The spring is connected with one end to the disk 143 and with its opposite end to a pin 145 secured to the plate 103. On the front side of the disk 143 a pawl 146 is pivotally mounted which is adapted to engage in the teeth of the ratchet wheel 142. To the rear of the disk a lug 147 is soldered which is in contact with a pin 148 projecting from the rack 102.

From the drum 139 the marking web is passed over a pin 149 and along a casing 150 inclosing the stamp or punch to a marking stamp 151. The casing 150 is secured to the plate 103 by means of screws 174 and 175. By means of the punch 151 the marks which are printed on the web 132 are punched out from the web 132 and placed on the web of fabric by means of a striper, the operation being such that the edge of the punch 151 does not get in contact with the web of fabric. To the head of the marking punch screws 153 and 154 are secured which are engaged by a bifurcated lever 155 mounted with its shaft 80 in a sleeve 156 fitted in a bore of the plate 103. To one end of the shaft a bifurcated crank arm 157 is secured by means of a screw 158. With the rod 94 in the released position shown in the figures in full lines 85 a pin 159 screwed to the rod 94 engages in the bifurcated part of the crank arm 157. Thereby the punch 151 and the striper 152 are set in the positions shown in the figures. On the stem of the striper 152 a coiled spring 160 is located which is disposed within a bore of the punch 151 and has the tendency to retract the striper 152 into the punch 151. In the position of the parts shown in Fig. 13 one of the arms of a lever 95 161 mounted on the crank arms 155 has been brought into engagement with a screw 162. Thereby the other arm of the said lever has been brought into engagement with the head of the stem of the striper 152, so that the 100 striper 152 has been shifted out of the punch 151 against the action of the spring 160. The lever 161 is supported on a pivot 163 fitted in the head of the punch 151.

Before a mark is punched from the web 105 132 a U-shaped web clamping frame 164 straddling the casing 150 presses the web against the punch casing 150. The web clamping frame is provided with a bore permitting the passage of the punch 151 therethrough, and it provides a matrix for the punch 151. In order that the clamping frame can be retracted from the marking web, as must be done whenever the web is being advanced, the arms of the web clamping frame 164 are connected with arms of bell crank levers 165, 166 located one at each side of the casing 150, which arms engage pivots 167 and 168 secured to the clamping frame. The bell crank levers 165, 166 have 110 115 rocking supports on a pivot 169 secured to the casing 150. Both bell crank levers have exactly the same form and they are formed with elongated holes 170 which are engaged by cams 171 and 172 secured to a shaft 173. The shaft 173 is mounted in bearings provided on the punch casing 150, and it passes through the plate 103 and carries at its 120 opposite end a disk 176. At the rear of the disk 176 a disk 177 is loosely mounted on the 130

shaft 173 and the hub of the said disk has the gear wheel 126 secured thereto. On the disk 177 a pawl 178 has a rocking support which is located at the rear of a shoulder formed on the disk 176 and is adapted to rotate the disk 176 and the shaft 173 in the direction of the arrow shown in Fig. 11, when the rack 102 is being shifted from its position shown in full lines into the position shown in dotted lines. Simultaneously the pawl 178 is moved into the position shown in dotted lines and it is retracted from the disk 176 by striking a pin 179.

On the shaft 173 a back pressure lever 180 is mounted which carries a wedge 181, which can be set by means of a screw 182. By means of the back pressure lever 180 the clamping frame 164 is released from the shocks which are caused when the pawl 178 is retracted from the disk 176, and the disk and the shaft 173 are thrown by a spring 183 in the direction of the arrow shown in Fig. 11. The spring is secured with one end to the shaft 173 and with the other one to a pin secured to the plate 103.

After the mark has been punched from the web, the latter is fed away from the punch casing 150 and supplied to a roll 185 which is mounted on a stub shaft 186 and is held in position by means of a screw 188 engaging in an annular groove 187 of the stub shaft, as is shown in Fig. 12. To a hub of the roll 185 a ratchet wheel 189 is secured, as is shown in Fig. 14. The stub shaft 186 is secured to a plate 190 which is and is held in position by means of a screw 191, 192, 193, 194. At the rear of the plate 190 a dish shaped disk 195 is loosely mounted on the stub shaft 186, which has a perforated bottom having a further aperture 196 permitting the passage of the hubs of pawls 197, 198, and a gear wheel 199, which are supported on pivots 200, 201, and 202 respectively. To the bottom of the dish shaped disk 195 a pin 203 is secured which passes rearward and through a slot 204 of the disk 190. The perforated bottom of the disk 195 is formed with internal teeth over a part of its circumference, and the teeth are in mesh with the pinion 199. Around the disk 195 a spring 205 is coiled which is secured with one end to the margin of the disk and with the opposite end to the pin 184. The spring tends to rotate the disk 195 in the direction of the arrow shown in Fig. 13. Between the bottom of the disk 195 and the ratchet wheel 189 of the roll 185 a segment 206 is loosely mounted on the pivot bolt 186, and on the said segment pawls 207 and 208 are mounted for engagement with the teeth of the ratchet wheel 189. The pawls 197 and 198 are likewise adapted to engage in the said ratchet wheel. To the hub of the segment 206 a gear wheel 209 is secured which is in engagement with the

pinion 199. As the spring 205 has the tendency to rotate the disk 195 in the direction of the arrow shown in Fig. 13, the segment which is connected with the disk 195 through the wheels 199 and 209 tends to rotate in the opposite direction. By the engagement of the pawls 207 and 208 in the ratchet wheel 189 the segment is adapted to carry along the roll 185 and to wind the web 132 on a sleeve 131 made from card board or the like. The spring 205 is put under tension by means of a hook 210 secured to the rod 94, which hook engages the pin 203 when the rod 94 is being released and rotates the disk 195 and the segment 206 into the position shown in Fig. 13 through the intermediary of the gear wheels 199 and 209.

In the example shown in the drawings the web of fabric is marked by gluing marks thereto. Therefore the marks which have a suitable gluing substance applied to their rear sides must be moistened prior to being punched from the web. For this purpose a moistening apparatus is mounted on the bar 2 which will be described hereinafter. On a slide bed 211 which is secured to the bar 2 by means of screws 212 and 213 a slide 214 is mounted which is formed with ears 214^a disposed at right angles thereto. To the said ears a valve casing 215 is secured by means of screws 216, 217 and 218. The slide 214 is formed with rack teeth 219 which are in mesh with the teeth of a gear wheel 220 secured to the shaft 220^a carrying the gear wheel 125 and guided in a sleeve 221 of the plate 103. Thereby the slide takes part in the movement of the rack 102 and moves always in the direction opposite to that of the rack 102.

The valve casing 215 consists of two parts which are held together by screws 222, 223, and 224. In cavities of the valve casing there are valve plugs 225 and 226 which are connected with crank arms 229 and 230 respectively by screws 227 and 228. The shafts 229^a and 230^a of the said crank arms are passed through bushings 229^b and 230^b of felt or the like fitted in bores of the side wall of the casing 215, and at their outer ends they carry wings 231 and 232. These wings are acted upon by springs 233 and 234 which tend to force the plugs 225 and 226 with their ends into the passages 225^a and 226^a located in front of the same so as to close the same. The passage 225^a which is controlled by the valve plug 225 communicates with the passage of an angular pipe 235, and within the passage 226^a located in front of the valve plug 226 there is a plunger 236 which fits in a tight manner in the casing. At the outside of the valve casing 215 a disk 237 is provided on the plunger 236, which is pressed by a spring 238 in contact with the head of the plunger 236. A

screw 239 connects the head of the plunger 236 with a lever 240 which is mounted on the slide 214 at 241.

To the bar 2 a rubber tube 242 is connected which communicates at one end with the pipe 235 of the valve casing 215 and at its opposite end with a metal pipe 243. The latter is connected to the conduit of a rotary pump 244 the suction and pressure pipes of which are in communication with a receptacle 245 containing a suitable gluing medium. The rotary pump 244 is driven from the driving shaft 87 through a belt gearing.

In the position of the parts shown in Figs. 13, 15, and 16 the valve casing 215 has been moved toward the punch casing 150, and during the last part of this movement the laterally projecting arm of the lever 240 and the wing 232 of the crank 230 have been held back by the screws 246 and 247 respectively, whereby the plunger 236 has been shifted in the direction of the arrow and the valve plug 226 has been brought into the position shown in Fig. 15. In the punch casing 150 a rubber plug 248 is fitted to protect the mouth of the valve casing from hard blows. By the movement of the plunger 236 in the direction of the arrow shown in Figs. 15 and 16 the gluing medium contained within the valve casing has been forced to the mouth 215^a of the casing, from which it has been delivered to the marking web 132. In a bearing 249 secured to the plate 103 a screw 246 is mounted, by means of which the stroke of the plunger 236 can be regulated as desired. Furthermore, in a bracket 249 a screw is mounted which provides a stop for the wing 231 of the crank 229 (Fig. 18) when the slide 214 and the valve casing 215 are retracted from the punch casing 150 and the marking web 132. As the wing 232 is being removed from the screw 247, the valve plug 226 which is acted upon by the spring 234 closes the passage 226^a which is located in front of its end. Simultaneously the plunger 236 is pulled by its spring 238 out of the valve casing 215 to such an extent, that the disk 237 bears on a pair of lugs 251 provided on the slide 214. Thereby the plunger sucks in the glue which has not been used into the passage of the mouth 215^a of the valve casing and thereby prevents the glue from dripping off the mouth of the valve casing. Before the end of the return movement of the slide 214 the wing 231 engages the screw 250 and opens the passage 225^a which is located in front of the valve plug 225, while the lever 240 engages the screw 252 and the plunger is withdrawn from the valve casing 215 farther than would be possible, if the spring 238 alone were provided for this purpose. As the plunger is being moved farther outward, the gluing medium which is being supplied

by the rotary pump 244 and through the tube 242 is drawn in by suction. If in the next operation the slide 214 is again moved toward the punch casing 150, the valve plug 225 closes at first the passage 225^a which is located in front thereof, thereupon the valve plug 226 is retracted from the passage 226^a located in front of its end, and simultaneously the plunger 236 forces the gluing medium which has been drawn in by the previous operation and the one which has been newly received is forced by the plunger 236 through the passage of the mouth 215^a of the valve casing 215 in order to moisten the next mark.

After the mechanism has thus been described in detail I shall now describe the operation. As appears from the drawings, the pair of clamping bars 1 and 2 has clamped the web of fabric 43 and carries the same along in the direction of the arrow shown in Fig. 1. In the position shown in the figure, the pair of clamping bars 1 and 2 have already passed beyond the pin 124 secured to the plate 15, so that the locking pawl 101 has been retracted from the rod 94, and the said rod has been shifted by the pressure of the spring 99 in the direction of the arrow. By reason of this displacement of the rod 94 the hook 210 has taken hold of the pin 203 and has rotated the disk 195 into the position shown in Fig. 13. In a similar way the pin 159 secured to the rod 94 and striking on the crank 157 has caused the punching of a mark from the web of marking paper and shifted the punch into the position shown in Fig. 13. Simultaneously with the rod 94 the rack 102 has been moved, so that the pawl 178 has been brought from the position shown in dotted lines into the position shown in full lines, and the pin 148 which is located in front of the lug 147 of the disk 143 has moved the said lug and together therewith the disk 143 from the positions shown in dotted lines into the positions shown in full lines. Simultaneously, by means of the gear wheels 125 and 220 the valve casing 215 of the moistening apparatus has been shifted toward the marking web 132, as is shown in Fig. 18.

Now the pair of clamping bars 1 and 2 and the marking apparatus mounted thereon move in the direction of the arrow shown in Fig. 1, until the reversing of the movement is started and the parts are in the positions shown in Fig. 2. As the direction of the movement of the pairs of clamping bars is reversed, the bar 2 is retracted from the bar 1, while the pair of clamping bars 3 and 4 is closed. As the bar 2 is being lifted from the bar 1, the pivot 111 of the crank 110 engages in the slot 115 of the gear wheel 114. After the bar 2 has come to its uppermost position, the crank pin 111 which so far was out of engagement with the end walls of the slit 115

is carried along by the wheel 114, so that by means of the wheels 109, 107, 106, the rod 94 is slowly advanced in the direction of the arrow, until the nose 100 arrives in the position shown in dotted lines and the pawl 101 locks the rod 94 in position. The rod arrives in this position shortly before the clamping bars 1 and 2 must again be closed. When the movement of the rod 94 in the direction 10 of the arrows is started, the pin 159 moves the crank 157 more and more into the position shown in dotted lines, so that the marking punch 151 is retracted into the punch casing 150. By reason of the construction of 15 the crank 157, at the end of one third of the whole path of the pin 159 the punch has been fully retracted into the casing 150 and is stopped therein. Simultaneously the pin 148 of the rack 102 moves together with the rod 20 94, so that the disk 143 can be rotated by the spring 144 in clockwise direction in Fig. 13. Thereby the pawl 146 of the disk 143 is gradually brought into engagement with a tooth of the ratchet wheel 142 of the drum 25 139, so that it can rotate the said drum. The rotation is started shortly after the marking punch has been retracted into the casing 150. But as the pawl 146 approaches a tooth of the ratchet wheel 142, also the pawl 178 and 30 the disk 177 are moving into the position shown in dotted lines because the rack 102 takes part in the movement of the rod 94. Thereby the shaft 173 is rotated in the direction of the arrow shown in Fig. 11, so that 35 the web clamping frame 164 is retracted from the punch casing an amount which corresponds to the eccentricity of the cam 171. When the pawl 146 engages a tooth of the ratchet wheel 142 the drum 139 is rotated by the spring 141 acting on the disk 40 143 in clockwise direction in Fig. 13, so that the conical pins 140 of the drum 139 which engage in the perforations of the web of marking paper 132 take the web from the roll 130, while the roll 185 which is acted 45 upon by the spring 205, the pawls 207 and 208 and the ratchet wheel 189 takes up so much of the web as is supplied by the drum 139. As at the beginning of the movement 50 of the web the clamping frame 164 had already been slightly retracted from the punch casing by the cams 171 and 172 and the bell crank levers 165, 166, the winding and unwinding of the web coincide. Thereby 55 strains on the marking web are prevented and a precise operation is assured. A period of the unrolling of the marking band 132 is completed, when the lug 147 of the disk 143 shown in Figs. 11 and 13 is in contact with 60 the screw 254 secured to the plate 103 and is locked as against further movement. When this is the case, the shank of the pawl 178 engages the pin 179 shown in Fig. 11 in order 65 to retract the other arm from the disk 176, whereupon the shaft 173 is thrown back into

the position shown in Figs. 12 and 13 by the spring 183 and presses the web clamping frame against the casing 150 so as to hold the marking web 132 in position for being again punched upon the following operation. 70 At the beginning of the movement of the rod 94 the valve casing 215 of the moistening apparatus has been retracted from the punch casing by the wheels 125 and 220 and the slide 214. The operation of the inner parts 75 of the valve casing have already been described.

The pin 138 is mounted on an arm 256 which has a rocking support on a pivot 255. Within a bore of the pin 138 there is a locking pin 257 which is pressed by a spring 258 into a bore of the plate 103. In order that the sets of marks printed on the web 132 can be set on the desired mark when stopping the machine, I prefer to construct the apparatus in such a way that the marking web can be removed from the drum 139. For this purpose the locking pin 257 is retracted from the plate 103 by means of a button 259 and against the tension of the spring 258, and the pin 138 and the arm 256 are brought into the position shown in Fig. 13 in dotted lines. After the pair of clamping bars 1 and 2 has again been closed, the gearing shown in Fig. 10 has again assumed the position 85 shown in the figure, and after the rod 94 has been released from the pawl 101 a new mark 90 is glued on the web of fabric in the same way as has been described.

I claim herein as my invention: 100

1. In a machine for marking webs of fabric or the like, the combination with a pair of clamping means reciprocating in line with each other and in opposite directions toward and away from each other, of means to throw the clamping means alternately in clamping engagement with the web for feeding the same, a movable carrier adapted to support the web being fed substantially over the whole part thereof which 105 is engaged by the clamping means and located in position to have the web clamped thereto by the clamping means, and means to apply marks to the web while being fed by the clamping means. 110

2. In a machine for marking webs of fabric or the like, the combination with a pair of clamping members, of means to reciprocate said clamping members in line with each other and in opposite directions 115 toward and away from each other, means for alternately throwing the clamping members into clamping engagement with the web being fed between the same, and means to apply marks to the web while being fed through the plane. 120

3. In a machine for marking webs of fabric or the like, the combination with a pair of clamping members, of connections 125 between said clamping members for move- 130

- ment in opposite directions, common means to reciprocate said clamping members in line with each other and in opposite directions toward and away from each other, 5 means for alternately throwing the clamping members into clamping engagement with the web being fed between the same, and means to apply marks to the web while being fed through the plane.
- 10 4. In a machine for marking webs of fabric or the like, the combination with a pair of clamping means reciprocating in line with each other and in opposite directions toward and away from each other, of 15 means to throw the clamping means alternately in clamping engagement with the web for feeding the same, a movable carrier adapted to support the web being fed substantially over the whole part thereof which 20 is engaged by the clamping means and located in position to have the web clamped thereto by the clamping means, a connection between one of said clamping means and the carrier adapted when reciprocating the 25 clamping means and during both strokes thereof to impart to the carrier movement in the feeding direction, and means to apply marks to the web while being fed by the clamping means.
- 30 5. In a machine for marking webs of fabric or the like, the combination with a pair of clamping means reciprocating in line with each other and in opposite directions toward and away from each other, of 35 means to throw the clamping means alternately in clamping engagement with the web for feeding the same, a movable band adapted to support the web being fed substantially over the whole part thereof which 40 is engaged by the clamping means and located in position to have the web clamped thereto by the clamping means, rolls on which said band is wound, chain gearings and clutches connecting one of said clamping 45 means and rolls and adapted during both strokes of the clamping means to impart to the roll unwinding rotary movement in the same direction for feeding the band together with the web, and means to 50 apply marks to the web while being fed by the clamping means.
- 55 6. In a machine for marking webs of fabric or the like, the combination with a pair of clamping means connected with each other for movement in line with each other and in opposite directions, gear wheels provided one at opposite sides of one of the clamping means, upper and lower racks disposed for alternate engagement with said 60 gear wheels, driving means for rotating the gear wheels in the same direction, means operative when the gear wheels arrive at the ends of the racks to throw the same out of engagement with the racks engaged thereby and into engagement with the other 65 thereby and into engagement with the other
- racks coöperating therewith, means operative when the clamping means are at the ends of their strokes to throw the same respectively in and out of clamping engagement with the web, and means to apply marks to the web while being fed by the clamping means. 70
7. In a machine for marking webs of fabric or the like, the combination with a pair of clamping means connected with each other for movement in line with each other and in opposite directions, gear wheels provided one at opposite sides of one of the clamping means, racks comprising continuous upper, lower and lateral sections and disposed for successive engagement with said gear wheels, driving means for rotating the gear wheels in the same direction, means operative when the gear wheels arrive at the ends of the racks to throw the same out of engagement with the racks engaged thereby and into engagement with the other racks coöperating therewith, means operative when the clamping means are at the ends of their strokes to throw the same respectively in and out of clamping engagement with the web, and means to apply marks to the web while being fed by the clamping means. 80
8. In a machine for marking webs of fabric or the like, the combination with a pair of clamping means connected with each other for movement in line with each other and in opposite directions, guide bars one on each side of the clamping members for guiding both of said clamping means and formed with upper, lower and lateral guide ways adapted to be successively passed by the clamping means, gear wheels provided one at opposite sides of one of the clamping 90 means, upper and lower racks disposed for alternate engagement with said gear wheels, driving means for rotating the gear wheels in the same direction, means operative when the gear wheels arrive at the ends of the racks to throw the same out of engagement with the racks engaged thereby and into engagement with the other racks coöperating therewith, and means to apply marks to the web while being fed by the clamping means. 95
- 100 9. In a machine for marking webs of fabric or the like, the combination with a pair of clamping means each comprising two members and reciprocating in line with each other and in opposite directions toward and away from each other, of mechanism on one of the clamping means for applying a mark to the web being fed, means operative when reversing the direction of the movement of the clamping means and at one end of the strokes thereof to throw the same into clamping positions, and mechanism intermediate the clamping means adapted when 105 reacted upon by either one of the clamping 110 means. 115
- 120 125 130

means being thrown into clamping position to throw the other clamping means in non-clamping position.

10. In a machine for marking webs of fabric or the like, the combination with a pair of clamping means each comprising two members and reciprocating in line with each other and in opposite directions toward and away from each other, of mechanism on one of the clamping means for applying a mark to the web being fed, said mark applying mechanism comprising a spring actuated driving member adapted to be moved for storing power in its spring during movement of the clamping means in one direction and to be shifted by its spring during movement of the clamping means in the opposite direction, and operative connections between the driving member and the operative parts 20 of the mark applying mechanism.

11. In a machine for marking webs of fabric or the like, the combination with a pair of clamping means each comprising two members and reciprocating in line with each other and in opposite directions toward and away from each other, of mechanism on one of the clamping means for applying a mark to the web being fed, said mechanism comprising means for supplying a web of 25 marking paper, spring actuated web feeding means, spring actuated means for winding the web, punching means and a spring actuated driving member connected with said web feeding and winding means and 30 punching means and adapted to be shifted in opposition to its spring when the clamping means are moving in one direction and to be shifted by its spring when the clamping means are moving in the opposite direction 35 and adapted to be shifted in opposition to its spring when the clamping means are moving in one direction and to be shifted by its spring when the clamping means are moving in the opposite direction and when thus moved to store power in the springs of the web feeding and winding means, to shift the 40 slide and the moistening apparatus mounted thereon into moistening position and to operate the same, and to operate the punching means and thereafter to permit operation of the power feeding and winding means by the springs thereof and to retract 45 the punching means and the slide carrying the moistening means into inoperative position.

and thereafter to permit operation of the power feeding and winding means by the springs thereof and to retract the punching 45 means into inoperative position.

12. In a machine for marking webs of fabric or the like, the combination with a pair of clamping means each comprising two members and reciprocating in line with each other and in opposite directions toward and away from each other, of mechanism on one of the clamping means for applying a mark to the web being fed, said mechanism comprising means for supplying a web of marking paper, spring actuated web feeding means, spring actuated means for winding the web, punching means, a slide and a moistening apparatus mounted thereon, and a spring actuated driving member connected with said web feeding and winding means and punching means and adapted to be shifted in opposition to its spring when the clamping means are moving in one direction and to be shifted by its 60 spring when the clamping means are moving in the opposite direction and when thus moved to store power in the springs of the web feeding and winding means, to shift the slide and the moistening apparatus mounted thereon into moistening position and to operate the same, and to operate the punching means and thereafter to permit operation of the power feeding and winding means by the springs thereof and to retract 65 the punching means and the slide carrying the moistening means into inoperative position.

In testimony whereof I hereunto affix my signature in the presence of two witnesses. 80
